CONRAD KERN, OF ZURICH, SWITZERLAND.

DRESSING-HAMMER.

1,212,502.

Specification of Letters Patent.

Patented Jan. 16, 1917.

Application filed February 16, 1915. Serial No. 8,664.

To all whom it may concern:

Be it known that I, CONRAD KERN, a citizen of the Republic of Switzerland, residing at Zurich, Switzerland, have invented new

and useful Improvements in Dressing-Hammers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Known stone dressing hammers, having interchangeable cutting heads, have a cavity formed in the hammer body to receive a pin or tenon formed on the cutting head. It has been found, however, that it is not advisable to provide the head piece with such a tenon, as the life of the head piece is very short, so that its cost of manufacture should be as small as possible. If the head piece and the tenon form one piece the machining of the tenon increases, however, the cost of the whole piece to such an amount that it is quite impossible to manufacture such head pieces on a large scale. For this reason it has been proposed to manufacture the tenons separately and to press them afterward into the head piece. This proceeding has however, the drawback that the tenon is not always inserted in exactly a vertical position into the head piece, in which case the latter does not fit snugly on the hammer body when it is secured thereto. This renders the handling of the hammer much more difficult and it influences in a detrimental manner the quality of the work obtained. Moreover, if the head piece does not fit properly on the hammer body it is much more liable to break.

The present invention consists in providing the detachable cutting head with a cavity adapted to receive a pin or tenon formed integral with the hammer body for the purpose of overcoming the above named objections. The cavity and tenon are designed to permit an angular movement of the head on the tenon in order to change the position of the cutting head on the body so that the cutting teeth on the edges of the head may be brought into different positions as the teeth become worn, as in a hand operated hammer. According to one convenient embodiment of my invention I pro-

vide said tenon with a slot and I secure the head piece to the hammer body by means of a tapering pin pressing the slotted parts of the tenon inserted into said cavity outward and against the walls of the latter. In such dressing hammers having an interchangeable head piece and a tenon forming a whole with the hammer body it is, however, essential that the diameter of the cavity of the head piece, into which the tenon has to be inserted, corresponds exactly to the diameter of the tenon, in order that the different head pieces may be fixed without further ado to the hammer body and in order to secure a good fitting of the head piece on the tenon and a proper working with the hammer. To prevent the pin which presses the slotted hammer body outward from projecting too much beyond the side faces of the hammer body, in which case it would be in the way of the workman and prevent a proper handling of the hammer, it is necessary that said tapering pin is always driven exactly the same amount into the hammer body, when a new head piece is fixed to said body. Further, it has been found that the head piece can be fixed in a particularly secure manner to the hammer body if the tenon of the hammer and the cavity of the head piece have a tapering shape of such a form that the head piece is prevented from moving away from the adjacent surface of the hammer body. A further advantage which may be attained by giving to the tenon and the cavity adapted to receive the latter a tapering shape consists in that the slotted tenon exerts the pressure effecting the connection between the head piece and the hammer body near its root upon said head piece when the fastening pin is inserted into the hole provided for it in the hammer. Owing to this arrangement a much better fitting of the head piece on said tenon is obtained and the quality of the work is very much increased, since such a tapering tenon has a very small elasticity. A tapering tenon acting in the hereinbefore described manner upon the surrounding parts of the head piece is also less liable to break when the hammer is handled in an inappropriate manner.

Several forms of carrying the invention into effect are shown by way of example in the accompanying drawings in which:

Figure 1 is a perspective view of a first construction, Fig. 2 is a front view on an

enlarged scale of the hammer body and the head piece fixed thereto of the hammer shown in Fig. 1. Fig. 3 is a side view, partly in section of the hammer parts shown 5 in Fig. 2; Fig. 4 shows on the scale of Figs. 2 and 3 a front view of a second embodiment of my invention; Fig. 5 is a side view partly in section of the parts illustrated in Fig. 4; Fig. 6 shows on the scale of Figs. 2 10 and 3 a front view of a third embodiment of my invention; Fig. 7 is a longitudinal section of the hammer parts illustrated in Fig. 6; Fig. 8 is a longitudinal section on a still larger scale through a part of the hammer 15 body and the head piece before the insertion of the tapering fastening pin; Fig. 9 is a corresponding view of these parts after the insertion of the fastening pin.

Similar numbers refer to similar parts 20 throughout the several views.

1 denotes the hammer body. The front surface 2 of this body, to which is fixed the head piece provided with a cutting face, has a slightly tapering tenon 3. The hammer 25 body 1 has a longitudinal slot 4 passing also through the middle of the tenon 3. According to the embodiment of the invention shown in Figs. 2 and 3 the slot 4 is provided near the front surface 2 with concave 30 surfaces 5 forming part of a slightly tapering bore 5'.

6 denotes the head piece provided with a cutting face 7. The head piece has a cavity 8 adapted to receive the tenon 3.

35 9 denotes a tapering fastening pin, which may be inserted into the bore 5'.

18 denotes the eye adapted to receive the handle 19.

For the purpose of fixing the head piece 6 40 to the hammer body 1 shown in Figs. 2 and 3 said piece 6 is pushed in such a manner upon the tenon 3 that the end surface of the head piece 6 lying opposite the cutting surface of this piece touches the front surface 45 2 of the hammer body 1. The pin 9 is hereupon inserted into the bore 5', so that the slotted tenon 3 is pressed outward and against the walls of the cavity 8. (Fig. 9).

According to the embodiment shown in 50 Figs. 4 and 5 the pin 9 is replaced by a screw 10, which is screwed into the hammer body 1 to press a part of the latter lying on one side of the slot 4 and the tenon 3 outward.

According to the embodiment of the invention shown in Figs. 6 and 7 there is fixed 55 to each end surface of the hammer body 1 a head piece 6 having a cutting surface. The attachment of the head piece 6, which has to be fixed to the right hand end of the body 60 1, is effected in the same manner as in the embodiment shown in Figs. 3-4, with the difference that the bore 5' is drilled into the tenon 3, so that the tapering pin 9 passes also through this head piece. For the purpose of fastening the other head piece to the

left hand end of the hammer body 1 there is provided on this end a tenon 3' having an annular groove 10'. The head piece 6, which has to be pushed on the tenon 3' has a slightly tapering bore 11 disposed in such a 70 manner that a tapering pin 9' passing through this bore touches at one point the wall of the annular groove 10' so that this head piece is fixed to the hammer body as soon as said pin is driven tightly into the 75 bore 11.

Owing to the fact that the tenon 3 is provided in the hereinbefore described embodiment of the invention on the hammer body 1, it is possible to machine this tenon. The 80 proper taper is given the tenon in machining which increases only slightly the price of the whole hammer, since the more expensive hammer body may be used for a very long time and only the cheaper head 85 piece has to be scrapped after a short use. Moreover, the machining of the tenon 3 secures a snug fit of the head piece on the hammer body.

As may be seen in Fig. 9 the head piece 6 90 provided with a tapering cavity, which is fixed to the tenon 3, is prevented from moving away from the supporting face 2 of the hammer body 1 and the tenon exerts its pressure near its root upon the head piece 6. 95 As I have shown at the beginning of the specification these are features, which are essential for obtaining good results with such a hammer.

What I wish to claim is:

1. A dressing hammer comprising a hammer body having a tenon formed thereon, a detachable head having a cutting face on one side, and a cavity in the opposite side to receive the tenon and adapted to permit angular movement of the head, said cavity being of greater depth than the length of the tenon whereby said opposite side of the head engages the hammer body, and means to move the tenon into engagement with the 105 sides of the cavity to lock the head onto the body. 110

2. A dressing hammer comprising a body portion having an integral tenon and a central longitudinal slot extending through the tenon, a detachable head having a cutting face on one side, and a cavity in the opposite side to receive the tenon and adapted to permit angular movement of the head, said cavity being of greater depth than the 115 length of the tenon whereby said opposite side of the head engages the hammer body, and means to spread the tenon to engage the sides of the cavity and lock the head onto the body. 120

3. A dressing hammer comprising a body portion having an integral tenon and a central longitudinal slot extending through the tenon, a detachable head having a cutting face on one side, and a cavity in the opposite 125 side to receive the tenon and adapted to permit angular movement of the head, said cavity being of greater depth than the length of the tenon whereby said opposite side of the head engages the hammer body, and means to spread the tenon to engage the sides of the cavity and lock the head onto the body. 130

side having inwardly diverging walls and adapted to receive the tenon, said cavity being of greater depth than the length of the tenon whereby said opposite side of the head 5 engages the hammer body, and means to force the tenon against said diverging walls to lock the head onto the body.

4. A dressing hammer comprising a body portion having an integral tenon and a central longitudinal slot extending through the tenon, a detachable head having a cutting face on one side, and a cavity in the opposite side having inwardly diverging walls and adapted to receive the tenon, said cavity being of greater depth than the length of the tenon, whereby said opposite side of the head engages the hammer body, and a tapering pin passing transversely through the tenon and head.

20 5. A dressing hammer comprising a body portion having an integral longitudinally

slotted tenon extending beyond the end of the body, a detachable head having a cutting face on one side and a cavity in the opposite side to receive the tenon and adapted 25 to permit angular movement of the head, the outer diameter of the cavity being greater than the normal diameter of the tenon, the walls of the cavity diverging inward and of a greater length than that of the tenon, and 30 means to force the tenon into engagement with the walls of the cavity, whereby the opposing faces of the head and body are held in contact.

In testimony that I claim the foregoing 35 as my invention I have signed my name in presence of two subscribing witnesses.

CONRAD KERN.
